UNITED STATES PATENT OFFICE.

JOHN S. HOERNER, OF HIGHLAND, ILLINOIS.

FLYING-MACHINE.

1,285,180.

Specification of Letters Patent. Patented Nov. 19, 1918.

Application filed May 15, 1918. Serial No. 234,686.

To all whom it may concern:

Be it known that I, JOHN S. HOERNER, a citizen of the United States, residing at Highland, in the county of Madison, and 5 State of Illinois, have invented new and useful Improvements in Flying-Machines, of which the following is a specification.

This invention relates to flying machines, the broad object in view being to produce 10 a flying machine having certain characteristics of the lighter than air type and certain other characteristics of the heavier than air type, the machine embodying gas inflated wings, which also act as airplane 15 surfaces, the machine being adapted to be propelled at a rapid rate of speed and also to hover over any desired point.

A further object of the invention is to provide means for varying the lateral positive or negative dihedral angle of the inflated wings and airplane surfaces so that the machine may be caused to ascend and descend at any desired angle while maintaining the horizontality of the car or body 25 carrying the passengers or freight.

With the above and other objects in view, the invention consists in the novel construction, combination and arrangement of parts, herein fully described, illustrated and 30 claimed.

In the accompanying drawings:—

Figure 1 is a side elevation of the improved flying machine.

Fig. 2 is a vertical longitudinal section 35 of the same.

Fig. 3 is a front elevation of the machine.

Fig. 4 is a fragmentary horizontal section showing the means for changing the 40 angle of the wings.

Fig. 5 is a fragmentary elevation of the same.

Figs. 6 and 7 illustrate the maximum reverse angles of the wings.

45 The improved flying machine, in the preferred embodiment thereof, comprises an elongated body or car 1 which may be made of any desired dimensions, the same being shown as provided with numerous windows 2.

In one end of the car 1, there is arranged an engine 3, the shaft 4 of which projects beyond the end of the body and has fast thereon a driving propeller 5. At the opposite end of the body there is arranged a vertical rudder 6 and a horizontal rudder 7, suitable controls (not shown) ex-

tending into the car 1 within convenient reach of the operator. Axles 8 extend under the car and have supporting wheels 9 thereon. The machine is thus adapted 80 to be propelled either on the surface of the water or on land.

Extending upwardly from the car 1 are masts 10 and 11 of tubular formation. Said masts are substantially parallel to each other and have extending in opposite directions therefrom a series of tubular arms 12 which support gas inflated wings 13 at opposite sides thereof. The wings 13 are arranged in superposed series and are of hollow formation and also of cellular formation, being divided by partitions or diaphragms 14 into a number of cells so that in case one or more cells should become punctured, the other cells will not be affected. The tubular arms 12 are connected at their outer extremities to tubular wing spars 14' which also constitute gas manifolds. These combined spars and manifolds are preferably housed within the adjacent 80 edge portions of the wings 13 for the purpose of reducing head resistance. Gas connections or nipples 15 extend from the several manifolds 14 to the cells of the wings in order that all of the cells may be separately inflated. The tubular masts 10 and 11 extend into the car 1 where they are connected to a tank or generator 16. It will thus be seen that gas stored in said tank or generated in the car may be conducted to 90 all of the cells of the wings of the machine. Lifting propellers 17 are journaled on the masts 10 and 11 above the series of wings and may be driven by any suitable connections from the engine 3 or if desired 95 from a separate and independent engine.

The tubular connections 12 between the masts 10 and the inflatable wings comprise jointed sections having an actual movement in relation to each other, as indicated in Fig. 4. The means for locking the wings to positive or reverse dihedral angles as shown in Figs. 6 and 7, consists of arms 19 extending inwardly toward each other from opposite wings, said arms having their inner 105 end portions overlapped and formed with longitudinal slots 20 to receive pins 21 extending laterally from upright operating rods or bars 22. The rods or bars 22 extend downwardly into the car 1 where they are 110 provided with suitable handles 23 and guides 24. By pulling downwardly on the handles

23, the wings 13 may be rocked to an upwardly inclining or positive dihedral angle as shown in Fig. 6, and by pushing upwardly on the handle 23, said wings may be 5 rocked to a downwardly inclining or negative dihedral angle as shown in Fig. 7. In ascending, the wings will be made to assume a downwardly inclining angle as shown in Fig. 7, allowing the machine to ascend 10 more rapidly, the force of the down draft from the propellers 17 being deflected by said wings. When descending, the wings 13 will be rocked to the upwardly inclining angles shown in Fig. 6 for a quick descent, 15 or at a less angle for a slower descent, at which time the lifting propellers 17 may be stopped.

As compared with the ordinary lighter than air dirigibles or machines of the Zeppelin type, much less head resistance is 20 encountered as the air currents may pass between the superposed wings, the air thus acting to maintain the stability of the machine. The machine may also be driven at 25 a much greater speed with the same power as compared with the ordinary dirigible or Zeppelin machine. The size of the machine and the car 1 may be varied in accordance with the number of passengers or amount 30 of freight to be carried. The flying machine is capable of being manipulated either in 35 the air or on the ground or on the surface of the water and it may be brought to a stop in time so as to hover over a given point.

I claim:

1. In a flying machine, the combination of a body, propelling means, directional means, masts extending upwardly from said body, series of superposed gas inflated wings 40 arranged at opposite sides of said mast and

extending in a fore and aft direction in 45 planes substantially parallel to the longitudinal axis of the body, lifting propellers journaled on said masts above said wings, 50 said gas inflated wings having airplane surfaces, and means for varying the angles of 55 said wings to the horizontal.

2. In a flying machine, the combination of a body, propelling means, directional means, masts extending upwardly from said body, series of superposed gas inflated wings 55 arranged at opposite sides of said mast and extending in a fore and aft direction in planes substantially parallel to the longitudinal axis of the body, lifting propellers journaled on said masts above said wings, 60 said masts being of tubular formation and forming gas conduits, combined tubular wing spars and manifolds housed in said wings, tubular arms connecting said masts and manifolds, and a gas supply in said 65 body.

3. In a flying machine, the combination of a body, propelling means, directional means, masts extending upwardly from said body, series of superposed gas inflated wings 70 arranged at opposite sides of said mast and extending in a fore and aft direction in planes substantially parallel to the longitudinal axis of the body, lifting propellers journaled on said masts above said wings, 75 said masts being of tubular formation and forming gas conduits, combined tubular wing spars and manifolds housed in said wings, tubular arms connecting said masts and manifolds, a gas supply in said body, 80 and nipples connecting said manifolds with the cellular compartments of the wings.

In testimony whereof I affix my signature,

JOHN S. HOERNER.
